UNITED STATES PATENT OFFICE.

EDWARD SIDNEY ROSS, OF NORWICH, CONNECTICUT.

PUZZLE.

SPECIFICATION forming part of Letters Patent No. 769,407, dated September 6, 1904.

Application filed May 2, 1904. Serial No. 205,866. (No model.)

To all whom it may concern:

Be it known that I, EDWARD SIDNEY Ross, a citizen of the United States, residing at Norwich, in the county of New London and State 5 of Connecticut, have invented certain new and useful Improvements in Puzzles, of which the following is a specification, such as will enable those skilled in the art to which it appertains to make and use the same.

10 This invention relates to puzzles; and the object thereof is to provide a device of this class the solution of which is difficult, but may be accomplished by the exercise of care and skill in the manipulation thereof.

15 The invention is fully disclosed in the following specification, of which the accompanying drawings form a part, in which the separate parts of my improvement are designated by suitable reference characters in each of the 20 views, and in which—

Figure 1 is a plan view of my improved puzzle; Fig. 2, a section on the line 2 2 of Fig. 1; Fig. 3, a section on the line 3 3 of Fig. 1, and Fig. 4 a section on the line 4 4 of Fig. 1.

25 In the practice of my invention I provide a base-plate *a*, which is preferably circular in form and to the top of which is secured a plurality of concentric walls *b*, *c*, *d*, and *e*, forming annular chambers *f*, *g*, and *h* and a central circular chamber *i*. The concentric walls *b*, *c*, *d*, and *e* are arranged in the order named beginning with the perimeter of the base *a*, and the annular chambers *f* and *g* are placed in communication by vertically-arranged pass- 30 ages *c*² in the wall *c*, while the annular chamber *h* and central chamber *i* are placed in communication by a passage *c*² in the wall *c*, said passage being in the form of construction shown in the same radial line with the passage 35 *c*² in the wall *c*.

40 Arranged transversely of the central chamber *i* is a vertical wall *j*, which extends above the concentric walls *b*, *c*, *d*, and *e*, and a wall *k*, which in the form of construction shown 45 extends above the wall *j*, and the walls *j* and *k* are connected by side walls *m* and a top wall *n*, so as to form a central transverse supplemental chamber *o*, and for the purposes of this description the wall *j* will be called 50 the "front" wall of the chamber *o* and the

wall *k* the "back" wall thereof. The bottom portion of the wall *k* extends backwardly horizontally, as shown at *k*², to the rear portion of the center concentric wall *e*, with which it is connected, as shown at *k*³, and the bottom portion *o*² of the chamber *o* is thus made larger than the top portion of said chamber, the back portion thereof being segmental in form and being bounded by the back portion of the concentric wall *e*. As thus constructed it will 55 be seen that the central chamber *i*, formed by the wall *e*, is divided so as to form a supplemental chamber *o*, the bottom portion *o*² of which is much wider than the top portion thereof, and connected with the top of the 60 outer wall *b* is a shield *p*, which extends forwardly over the concentric chambers *f* and *g* and with which is connected centrally thereof a runway *s*, which communicates at its rear end with the annular chamber *f* and at its 65 front end with the chamber *o* between the walls *j* and *k*, and the wall *j* is provided with a central opening *j*², which communicates with the runway *s* and in the form of construction shown with two laterally-arranged openings 70 *j*³, which communicate with the chamber *o*. The vertically-arranged back wall *j* of the chamber *o* is wider and higher than the wall *j* in the form of construction and is provided at its 75 opposite sides with forwardly-directed wings or members *k*⁴ and with a forwardly-directed top member *k*⁵, whereby side spaces *k*⁶ and a top space *k*⁷ are formed, which spaces open forwardly and are placed in communication and also in communication with the inner annular 80 chamber *h*, and the forward end of the runway *s* is also in communication with the space *k*⁷, as shown at *s*². I also provide a plurality of balls or spherical bodies *t*, any desired number of which may be employed, but six 85 of which are shown in the drawings, and these balls or bodies may be placed at any desired point in any of the annular chambers *f*, *g*, and *h*; but, as shown in Fig. 1, they are placed in the annular chamber *f*, and the 90 solution of the puzzle consists in manipulating the device so as to pass said balls or bodies into the chamber *o* or into the part *o*² thereof. In this operation the device is manipulated so as to pass said balls into the central chamber 95 100

i and then roll the same over the face of the wall *j* of the chamber *o* into the openings *j*³, which communicate with the chamber *o* and with the bottom portion *o*² of said chamber. 5 In the latter part of this operation care must be taken to prevent the balls or bodies from rolling off of the surface of the wall *j* into the runway *s* or into the spaces *k*⁶, in which event they roll back into the annular chambers *f*¹⁰ and *h*. With a single ball or body the solution is comparatively simple; but with a plurality of said balls or bodies the solution becomes exceedingly difficult; but the same may, as hereinbefore stated, be accomplished by the 15 exercise of care and skill in the manipulation of the device.

It will be observed that the front edges of the parts or members *k*⁴ and *k*⁵, which are connected with the vertically-arranged wall *k* and, 20 in fact, form a part thereof, are flush with the face of the wall *j* in the form of construction shown; but this arrangement of said parts is not absolutely necessary, all that is necessary in this connection being to provide 25 the spaces *k*⁶ and *k*⁷, which may be of any transverse depth or thickness, and it will be apparent also that other changes in and modifications of the construction herein described may be made without departing from the spirit 30 of my invention or sacrificing its advantages.

Having fully described my invention, what I claim as new, and desire to secure by Letters Patent, is—

1. A puzzle comprising a base-plate, a plurality of concentrically - arranged annular walls secured thereto and between which are corresponding concentric annular chambers which are placed in communication at different points and within which is a central chamber 35 also in communication with the inner concentric annular chamber, said central chamber being divided by vertically-arranged walls which extend above the concentric annular 40

walls and by means of which a supplemental chamber is formed, a runway extending from one of said annular chambers upwardly and forwardly and through said vertically - arranged walls and through said supplemental chamber, the front wall of the supplemental chamber being also provided with an opening 50 which communicates with said runway and with other openings communicating with said supplemental chamber, substantially as shown and described.

2. A puzzle comprising a base-plate, a plurality of concentrically - arranged annular walls secured thereto and between which are corresponding concentric annular chambers which are placed in communication at different points and within which is a central chamber 55 also in communication with the inner concentric annular chamber, said central chamber being divided by vertically-arranged walls which extend above the concentric annular 60 walls and by means of which a supplemental chamber is formed, a runway extending from one of said annular chambers upwardly and forwardly and through said vertically - arranged walls and through said supplemental chamber, the front wall of the supplemental 65 chamber being also provided with an opening which communicates with said runway and with other openings communicating with said supplemental chamber, and said supplemental chamber being also inclosed at the sides and 70 top thereof by spaces or chambers which open forwardly, substantially as shown and described.

In testimony that I claim the foregoing as my invention I have signed my name, in presence of the subscribing witnesses, this 26th day of April, 1904.

EDWARD SIDNEY ROSS.
